UNITED STATES PATENT OFFICE.

PHILIP PHOEL, OF NEW DORP, NEW YORK.

JEWELER'S TWEEZERS.

Application filed October 22, 1924. Serial No. 745,052.

To all whom it may concern:

Be it known that I, PHILIP PHOEL, a citizen of Holland, residing at New Dorp, Staten Island, in the county of Richmond and State of New York, have invented certain new and useful Improvements in Jewelers' Tweezers, of which the following is a specification.

This invention relates to holding and adjusting implements and more particularly to jewelers' tools adapted to facilitate operations upon rings and the like.

Among the objects of this invention is to provide a ring holding tool that will support a ring in predetermined position, and such other part as is to be affixed to the ring in predetermined relation or adjustment to the same.

Another object of this invention is to secure a spring or filler within a ring in a neat and inconspicuous manner and with as little labor as possible.

More particularly, this invention provides a holding tool for retaining an arcuate spring or filler that is to be secured to the ring along a periphery thereof in definite and adjusted relation to the plane of the ring, to permit said filler to be accurately soldered or otherwise fastened to the ring, or other desirable operation to be performed.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a perspective view of the tool.

Fig. 2 is an end view showing a typical use of the tool.

Fig. 3 is a perspective view showing the holding portion of the tool.

Fig. 4 is an enlarged side view with parts in section on the line 4—4 of Fig. 2 showing the adaptability of the tool for purposes of adjustment.

Referring now more particularly to the drawings, I show the holding tool as comprising a plurality of spaced strips or arms of sheet spring material 10 and 11 suitably fastened together at an end 12. Said arms are recessed at 13 and offset as at 14 to cross

each other whereby pressure exerted upon them at the arrows *a* will cause a movement of the extremities 10^a and 11^a away from each other as per arrows *b* so as to open the tool.

The arm 11^a is provided with a trident or the like comprising a plurality of spaced fingers the ends of which lie in a curve transverse to the length of the tool. Thus a central finger 15 is provided constituting a prolongation of the arm 11^a, and a pair of side fingers or branches 16, which are preferably struck from the same strip of metal as the arm 11^a. The ends of the fingers 16 lie in proximity to the end of the finger 15, but offset from the plane thereof so as to be in an arc therewith, said fingers being slightly bent for this purpose as shown. The ends of the fingers 16 are recessed or notched lengthwise at 17, the angles of the recesses being approximately those made by tangents to the arc aforesaid at the points thereof adjacent to the ends of the fingers 16. Thus an arcuate spring or filler 18 may be gripped and held in the trident by passing the central portion 17 of the spring beneath the finger 15 and the side or wing portions of the spring into the recesses 17.

The arm 10^a terminates in a suitable support comprising preferably a pair of arcuate fingers 21 which are concaved toward the fingers 15 and 16, said fingers being so curved as to snugly receive and support a ring 22 or the like. Thus while the trident grips the spring 18, the instrument may be opened and the ring 22 passed beneath the spring and seated upon the support 21. The springs 10 and 11 then bring the tool into closing position causing the spring or filler 18 to come into contact with the ring 22 along the inner surface thereof, thereby securely holding both the spring and the ring within the tool and in fixed and predetermined relation to each other. The spring 18 is of slightly less width than the ring 22 so as to lie concealed therein when worn upon the hand of the owner. To facilitate extreme accuracy for proper alignment of the two members, the spring 18 is dented or notched at the central portion 19 of the spring forming a lip 23. A groove 24 is formed in the finger 15 adjacent to the end thereof to receive said lip, thereby holding the spring against movement longitudinally of the tool, said groove being so located relatively to the seat 21 as to hold the spring

18 in proper relation to the ring as stated. The cup or pit 25 formed beneath the lip serves to contain the solder thus permitting a strong and neat joint to be made.

5 When the members are held in the tool as shown in Fig. 4, they may be secured together preferably as by soldering at the region of contact of the central portion 19 of the spring or filler and the ring, the holding tool being capable of withstanding a sufficiently high temperature to be unaffected. Thus a considerable saving of time and labor is obtained and a neat and satisfactory connection made.

15 I claim:

1. In a holding tool, the combination with a pair of relatively movable arms, of a plurality of fingers carried by one of them, one of said fingers having gripping means for holding an arcuate member, and a support carried by the other arm for holding a ring in contact with said member, at a point between said fingers and in substantially concentric relation to said arcuate member.

25 2. In a holding tool, the combination with a pair of relatively movable arms, of a plurality of approximately concentric spaced gripping means carried by one of them for holding an arcuate member, and a support carried by the other arm adjacent to the gripping means aforesaid and co-operating therewith to hold a ring seated within said support, in substantially concentric relation with said arcuate member and in contact with said member at a point between said gripping means.

35 3. The herein described holding tool comprising a pair of relatively movable arms, gripping means comprising a plurality of

40 fingers carried by one of said arms, one of said fingers being notched to receive an arcuate member and to lie above said member, and a support carried by the other arm, said support including a seat co-operating with said gripping means to hold a ring seated in the seat directly beneath said finger having the notch by causing the same to abut against the member aforesaid at the notched finger.

45 4. A holding tool comprising a plurality of fingers to hold an arcuate member, said fingers having gripping means for holding said member in slidable position lengthwise of the member, and other gripping means for holding the member against movement lengthwise of the fingers when gripped as stated, a support being provided movable relatively to said gripping means, said support being adapted to hold a ring in contact with and in substantially concentric relation with said member, said support being so located lengthwise of said fingers as to hold the member and the ring in substantially 60 parallel planes.

5. A holding tool comprising a trident, the central finger whereof is notched crosswise, the side fingers being recessed to receive a thin arcuate member and to hold the same slidably within said recesses, said central finger operating through the notch thereof to prevent movement of the member longitudinally of the fingers, said central finger lying within the member, and a support for carrying a ring without said member and through abutment thereof with the member and in the plane of the member.

In testimony whereof I affix my signature.

PHILIP PHOEL.
